UNITED STATES PATENT OFFICE.

JOSEF SCHÄFER, OF DORTMUND, GERMANY.

PROCESS OF SEALING VERTICAL COKING CHAMBERS.

Application filed December 3, 1920. Serial No. 328,171.

(GRANTED UNDER THE PROVISIONS OF THE ACT OF MARCH 3, 1921, 41 STAT. L., 1313.)

To all whom it may concern:

Be it known that I, JOSEF SCHÄFER, a citizen of Germany, and a resident of Dortmund, in the Republic of Prussia, Germany, have invented certain new and useful Improvements in Processes of Sealing Vertical Coking Chambers and the like (for which I have filed applications in Germany, April 28, 1919, Patent No. 331,253; Belgium, June 28, 1920, Patent No. 288,000; France, June 30, 1920, Patent No. 518,350; and England, July 2, 1920, Patent No. 145,782), of which the following is a specification.

Hitherto the sealing of vertical coking-chambers, or vertical retorts of coke-ovens, gas-works and similar industrial plants employed in the manufacture of gas has been accomplished by a water-seal. This was obtained by filling a stationary tray or the like with water, into which the lower part of said chambers or retorts dipped directly, or by means of an air-cooled extension, as is generally the case in continuous retorts. In the first instance, where the coke comes into direct contact with the water-seal when still in a highly incandescent state, the water is made to boil so violently, that suddenly much steam is generated which under considerable pressure generally forces its way outwards through the seal. In the second instance, where the uninterruptedly descending coke has lost much of its heat before it comes into contact with the water-seal, the generation of steam is on the contrary wholly insufficient.

In both cases the steam is therefore not generated in such a manner as to obtain the best results when it is mixed with the gases to expel the latter from the coking-chambers or retorts, because such steam is not produced in the proper proportion to the amount of gases being generated. To attain this proper proportion, the generation of the steam must regulate itself automatically during the entire process of dry distillation.

Another serious disadvantage of these water-seals is that the coke must be removed through the water-seal intermittently by hand, or continuously by mechanical means, which operations unduly increase the expenses of manufacture.

The object of my present invention is to

avoid the drawbacks of the water-seals now in use. I attain this end by a process of sealing according to which in the discharge-opening of each coking-chamber or retort, a moist-seal is arranged, which sucks up like a sponge the water subsequently to be converted into steam and presents such water to the more or less incandescent material in the exact proportion required at the different stages of the process of dry-distillation. In contra-distinction to this the mouth of each coking-chamber or retort is sealed by a granular dry-seal, which on being broken up for introducing a new charge automatically renews the granular constituent of the moist-seal destroyed by the discharge of the finished coke.

By means of this new process it becomes possible to generate at every stage of dry-distillation the required volume of steam quite automatically; further, to use the same sealing-agent successively for building up two seals of quite different ways of operation; and finally to discharge the carbonaceous product of dry-distillation more conveniently and at a smaller expense than hitherto.

In the accompanying drawing:—

Figure 1 is a longitudinal sectional view of a vertical coking-chamber sealed in accordance with my present invention, and

Figure 2 is a similar view thereof taken on line A—B at right angles to Figure 1.

The discharge-opening 1 of the vertical coking-chamber 2 is closed by means of a tray 3 hinged by pins 4 to brackets 5. These brackets are secured by a plurality of bolts 6 to an I-beam 7. The discharge-opening 1 is inclosed by an oblong frame 8. The lower edge 9 of this frame reaches below the rim 10 of the tray 3 which is locked in its horizontal position by one or more fingers 11 of the oscillating shaft 12. To secure the latter in its locking position it may be provided with one, or several counter-weighted arms 13, as shown, or with any other suitable locking-means. The shaft 12 is journaled in brackets 14 secured by a plurality of bolts 15 to an I-beam 16 and may be manipulated by means of a lever, hand-wheel or any other suitable device (not shown).

To form an effective seal at this junction of the frame 8 and the tray 3 a granular

sealing-agent 17, preferably coke-ashes, is introduced into the discharge-opening 1 through the hopper 18. By capillary action, these coke-ashes draw up the water supplied 5 by the water-pipes 19 to the tray 3 and form in conjunction with this water the moist-seal 20 always ready to supply the necessary water for the generation of steam in such quantities as demanded at any particular 10 stage of the process of dry-distillation. The charge 21 preferably coal, provided for the generation of gas is introduced into the coking-chamber through the hopper 18 and arranges itself upon the moist seal 20. 15 Finally the cover 22 is introduced into the hopper and at the junction of both parts a gas-tight dry-seal 23 is produced by filling the oblong cavity 24 formed thereby with a granular sealing-agent of exactly the same 20 nature as employed for the moist-seal 20, i.e. coke-ashes.

The operation of the coking-chamber when using my new process of sealing is as follows:—

25 At the beginning of the dry-distillation the generation of gases will naturally be slow so that the volume of steam necessary for mingling with these gases and driving them from the coking-chamber into the gas- 30 conduit 25 will be but small. This condition is assured by the fact that the low incandescence of the contents of the coking-chamber can evaporate but a small part of the water held in readiness by the moist-seal 35 20. When, however, the incandescence of the contents of the coking-chamber reaches a higher degree, more water will in consequence thereof be evaporated to mingle as steam with the greater volume of gases de- 40 veloped at this stage of the process of dry-distillation and to drive them off. For the same reason the greatest volume of steam will be generated at the close of the distillation-process although the volume of gases 45 developed at this part of the distillation-process will be smaller than previously when the contents of the coking-chamber still contain a far greater amount of volatile matter than at the close of the distillation- 50 process. But the amount of steam that might be saved on account of the smaller volume of gases is fully required by the comparatively great rise in the temperature of the gases developed at this final part of 55 the distillation-process. This smaller volume of gases is due to the fact that at this final stage of dry-distillation the contents of the coking-chamber constitute a carbonaceous body almost free from volatile 60 constituents. The comparatively great supply of steam to these highly heated gases most effectively prevents the decomposition of the ammonia contained therein, the particles of which the steam envelops and pro- 65 tects like a cloak.

After the coal has been completely converted into coke the tray 3 is swung aside and the coke thus deprived of its support will leave the coking-chamber and in so doing destroys the moist-seal 20. In order to prepare said chamber for a new operation the tray is swung back again into its working position and is locked therein by the aid of the fingers 11. To renew the moist-seal 20 as well as the charge 21 the cover 22 must be removed and in so doing the dry-seal 23 is destroyed and the coke-ashes previously used in building up this dry-seal will drop down through the coking-chamber, collect on the tray 3 and fill the discharge-opening 1 anew. The same coke-ashes previously employed in building up a dry-seal 23 will thus be used again for building up a moist-seal 20 adapted to perform its function as soon as the tray 3 is supplied with water. 70 80 After a new charge has been introduced and the cover 22 reinserted, a new dry-seal 23 will be built up by a fresh supply of coke-ashes, whereupon the dry-distillation may be recommenced.

I claim:—

1. The process of sealing vertical coking-chambers and the like by first, closing the discharge-opening thereof by a granular sealing-agent; second, keeping a liquid in 85 contact with said sealing-agent for forming a moist-seal adapted to draw said liquid up by capillary action and to hold it in readiness for evaporation as demanded by the process of dry-distillation; third, sealing the 100 charging mouth of said coking-chambers by a dry-seal consisting of a granular sealing-agent of the same nature as utilized in said moist-seal; fourth, removing said moist-seal by opening the discharge-opening and discharging the carbonaceous product of 105 dry-distillation; fifth, closing said discharge-opening and sixth, automatically transferring the granular sealing-agent of said dry-seal to said closed discharge opening for utilizing it as a sealing-agent in the building up of the subsequent moist-seal when said dry-seal is being broken up for the admission of a new charge, substantially as specified.

2. The process of sealing vertical coking-chambers and the like by first, closing the discharge-opening thereof by coke-ashes; second, keeping water in contact with said coke-ashes to form a moist-seal for drawing 110 said water up by capillary action and to hold such water in readiness for its conversion into steam by the process of dry-distillation; third, sealing the charging mouth of said coking-chambers by a dry-seal consisting of coke ashes; fourth, opening the discharge-opening to discharge said moist-seal together with the finished coke; fifth, closing said discharge-opening; and sixth, 115 transferring the coke-ashes of said dry-seal 120 130

automatically to said discharge-opening for utilizing said coke-ashes in the building up of a new moist-seal when said dry-seal is broken up for the admission of a new charge, substantially as specified.

3. The process of operating upright coking-chambers and the like, which consists in first, introducing a granular sealing-agent into the closed discharge-opening of such chamber or the like; second, charging the chamber with the material intended to be subjected to dry distillation and heating such material; third, supplying a liquid to said sealing agent to transform it into a moist-seal adapted to draw said liquid upward by capillary action and to present such liquid to said charge during the process of dry-distillation; fourth, sealing the charging mouth of said chamber by a dry-seal composed of a granular sealing-agent of the same nature as the sealing agent of said moist-seal; fifth, removing said moist-seal by the discharge of the dry-distillation product from said chamber; sixth, closing said discharge-opening; seventh, breaking up said dry-seal for the introduction of a new charge into the said chamber; and eighth, transferring the débris of said dry-seal by gravity to the closed discharge opening and utilizing such débris in the building-up of a new moist-seal.

4. The process of operating upright coking-chambers and the like, which consists in first, introducing coke-ashes into the closed discharge-opening of such chamber or the like; second, charging such chamber with

coal and subjecting said coal to dry-distillation; third supplying water to said coke-ashes to produce a moist-seal adapted to draw said water upward by capillary action 40 and to present such water to the heated coal during the process of dry-distillation for the conversion of such water into steam; fourth, sealing the charging mouth of such chamber by a dry-seal composed of coke-ashes; fifth, removing said moist seal and discharging the finished coke from such chamber; sixth, again closing the discharge-opening of such chamber; seventh, breaking up said dry-seal to clear the way for the introduction of a new charge into said chamber; and eighth, transferring the débris of said dry-seal by gravity to said closed discharge-opening and utilizing such débris for building up of a new moist-seal. 55

5. An upright coking chamber or the like, having a charging opening at the top, with a seat at the inner portion of said opening, means for temporarily sealing the lower end of said chamber, and a cover arranged to engage said seat and out of engagement, when seated, with the upper portion of said opening, thus leaving a space in said opening, above the cover, for the reception of a sealing material. 65

Signed by me Dortmund, Germany, this 5 day of November 1920.

JOSEF SCHÄFER.
